COVER FOR CURB BOXES AND THE LIKE

Victor Emanuel Beagle, Alexandria, Va.

Application March 4, 1947, Serial No. 732,206

1 Claim. (Cl. 220—55)

1
This invention relates to covers for curb boxes and the like. An object of the invention is the provision of cover for a curb box which may be supplied as a standard unit but which may be employed also as a replacement cover for various forms of curb boxes, said covers being readily applied and secured in position by several simple operations.

Another object of the invention is the provision of a simple and efficient cover for curb boxes in which a pair of depending flanges at the inner face of a flat circular plate of the cover cooperate with projections on the inner wall of the curb box for screwing the cover in position with a bolt threaded into said plate and engageable with one of the projection for retaining the cover against ready removal thereof.

A further object of the invention is the provision of a simple and efficient cover for curb boxes and the like in which a concentric flange depending from a circular flat plate of the cover being in snug contact with the inner wall of the cylindrical curb box cooperates with a fragment of a helicoidal web depending from the plate and threadedly receiving a lateral projection on the inner wall of the curb box for attaching the cover to said box, a bolt threaded into the flat plate engaging the lateral projection for clamping rigidly the cover to the box and preventing unauthorized turning of the cover.

The invention consists in the novel construction, arrangement and combination of parts hereinafter more particularly described and claimed.

In the drawings:

Figure 1 is a top plan view of cover for curb boxes constructed in accordance with the principles of the invention described herein.

Figure 2 is a bottom plan view of the cover.

Figure 3 is a view in perspective of the under face of the cover showing certain faces of a pair of depending flanges.

Figure 4 is a view in perspective of the cover similar to that illustrated in Figure 3 but disclosing the opposite faces of the flanges.

Figure 5 is a vertical section of the cover applied to a curb box, and

Figure 6 is a view in elevation of the curb box with a modified form of the cover.

Figure 7 is an enlarged fragmentary vertical section taken along the line 7—7 of Figure 6.

Referring more particularly to the drawings, 10 designates generally a curb box which is mounted in the ground adjacent the curb of a roadway. More specifically, however, the nu-

meral 10 indicates the bell flange at the top of the ordinary box. A lateral and horizontal flange 11 extends inwardly of a vertical offset 12 on the upper end of the bell flange. The free end 13 of the flange is curved concentrically and is disposed within said bell flange. A lug 14 is on the inner wall of the bell flange and diametrically opposite the lateral flange or lug 11. Said lug 14 is located below a horizontal plane passing through the lateral flange 11.

A cover for the curb box generally designated by the numeral 20 includes a flat circular plate or disk 21 which has a raised boss 22 on the upper surface forming a reinforced section of the plate 15 for a vertical passage 23 into which is threaded a bolt 24 having a slotted head 25 at the exterior of the cover 20. The bolt extends inwardly of the curb box so that the free end thereof may engage the flange 11 for a purpose to be presently explained.

The inner face of the plate has depending flanges 30 and 31 cast thereon. Flange 30 has a concentric outer wall which neatly fits the inner curved wall of the bell flange of the curb box as shown in Figure 5. One vertical edge is cut away as shown at 32 for engagement with the lug 14 which acts as a stop to limit turning movement of the cover 10. The opposite edge 33 of the flange 30 is sheared off at a slight angle to the vertical.

30 The flange 31 which in effect is a fragment or section of a helicoidal web has its base where attached to the underface of the plate 21 disposed eccentrically with a respect to said circular plate for a particular purpose. It will be noted

35 from Figures 4 and 5 that the web has a wide concave mouth 35 which is progressively tapered toward the reduced end 36 adjacent the bolt 24 so that the free end 13 of the flange or lug 11 may be received by the wide mouth 35 of the

40 helicoidal web 31 when the plate 21 is rotated with the helicoidal surface of the web moving along the free end 13. The eccentricity of the helicoidal web 31 provides a cam surface 34 which is adapted to contact the free end 13 of the lug 11

45 on the box 10 and such cam surface is effectively and progressively increased from the wide mouth portion 35 to the narrow concave portion 36 so that as the cover is turned toward its final or closed position the cam surface will tend to increase progressively its pressure on the free end of the lug 11.

In application, the cover is lowered on to the top of the curb box with the depending flanges 30 and 31 being received within the open end of 55 the box. The cover is so positioned over the

box in such manner that the cut-away portion 32 of the flange 30 is behind the lug 14 in Figure 5 so that the free end 13 of the lug or flange 11 will be in a position to be received by the wide mouth 35 of the helicoidal web. The cover is tilted at an angle to the horizontal and then pressed down on the box until the helicoidal surface 34 of the web 31 receives the lug 11. The cover is then rotated in the direction indicated by the arrow in Figure 5 until the vertical wall of the cut-away 32 of the flange 30 is in line with the lug 14. The cover is then pressed down on the box when the cut-away portion will be drawn into engagement with the lug 14.

During the rotation of the cover to its final position the free end 13 of the lug 11 rides on the helicoidal surface of the web 31 until the reduced portion 35 of said surface reaches the free end 13 where it is frictionally engaged with the surface. At this time, the flange or lug acting on the helicoidal surface tends to position the outer concentric wall of the flange 30 in snug contact with the inner wall of the curb box 10 so that the cover can not be tilted. The bolt 24 is then screwed downwardly with the free end of said bolt pressing on the lug 11. This bolt cooperates with the lug 14 to retain the cover in place.

When it is desired to remove the cover, the bolt 24 is loosened and the cover is tilted slightly to remove the cut-away portion 32 from the lug 14 and then rotated for releasing the helicoidal surface from the lug 11. The cover may then be lifted freely.

Due to the eccentricity of the helicoidal web 31 it is possible for said surface to act on the lug 11 for pressing the flange 30 against the wall of the box 10. Such eccentricity also causes the surface acting on the lug 11 to press the cover down on the box.

In the modified form shown in Figure 6, the cut-away portion in the concentric flange 30-a is in the form of a notch 32-a to receive the lug 14.

5 I claim:

A cover for a curb box provided with a lug and an inwardly disposed horizontal flange arranged diametrically opposite each other, said cover consisting of a flat disk having an eccentric helicoidal flange depending from the under face of the disk, a concentric flange depending from said under face and having a cut away portion extending upwardly from the lower edge thereof, the inwardly disposed horizontal flange of the curb box being engaged by said helicoidal flange for drawing the disk down onto the box upon rotation of the disk in one direction, and said lug engaging the cut away portion of the concentric flange for limiting rotation of the cover, and a bolt threaded in a vertical passage in the disk and being positioned at a point opposite the cut away portion of the depending flange, said bolt engaging said horizontal flange at right angles thereto for maintaining the cover against rotation and for drawing the concentric flange tight against the lug.

VICTOR EMANUEL BEAGLE.
